UNITED STATES PATENT OFFICE.

WILLIAM B. EASTON, OF CHICAGO, ILLINOIS.

ORE-STAMP.

No. 886,686.

Specification of Letters Patent.

Patented May 5, 1908.

Application filed May 31, 1907. Serial No. 376,483

To all whom it may concern:

Be it known that I, WILLIAM B. EASTON, a citizen of the United States, and a resident of Chicago, in the county of Cook and State of Illinois, have invented certain new and useful Improvements in Ore-Stamp, of which the following is a specification.

This invention relates to rock and ore crushers and relates particularly to that type of crusher known as stamp mills and which comprise, essentially, a lower fixed die, an upper, movable stamp or die, an upright rod which carries said movable stamp or die, a driven cam for intermittently raising said rod, together with the movable stamp or die, and releasing the same when in raised position, so as to permit the stamp to fall with crushing force upon the die beneath.

It has heretofore been attempted to apply a bell crank between the stamp lifting cam and the stamp rod with the idea of imparting a sudden downward impulse or kick to the stamp immediately it is released, with a view to increasing its momentum and the force of its impact when it strikes the lower die, or the material to be crushed resting thereon. So far as I am aware, however, all efforts to thus increase the impact of the movable stamp or die have been ineffectual for the reason that, with a lever coöperating with the raising cam, said cam and lever being properly proportioned to raise the movable stamp or die a desired distance and also to effectively accelerate the velocity of the stamp on its down stroke, the engagement of the cam with the lever will continue during so large a part of the down stroke, that the lever is liable not to pass out of the path of travel of the cam until after the stamp has been brought to rest. This may happen, for example, when an excessive quantity of ore or other material to be crushed accumulates on the lower die, and obviously, under these conditions, the lever will either offer such resistance to the rotation of the cam as to stop the mill, or, more probably, the continued rotation of the cam, will subject the mechanism to such severe stress as to cause a breakdown. On the other hand, if the lever is properly proportioned so that it will pass out of the path of travel of the raising cam before the movable stamp or die reaches the end of its downward stroke, it is found that the relation is such that the acceleration of the stamp is too slight to be of any practical effect.]

The principal object of the present invention is to provide improved means for increasing the impact of the stamp which will be effective and at the same time free from either of the objectionable features above enumerated.

A further object of the invention is to provide a safety device, whereby, in case of any extraordinary resistance offered to the downward movement of the stamp while the accelerating devices are still in engagement, one of the members will be broken in a predetermined place and manner, which admits of being quickly and conveniently fixed or remedied by means of inexpensive duplicate parts always at hand, thus avoiding long delays and consequent large expense, due not alone to the cost of the parts to be replaced, but to the probably much greater item of the loss of time due to the shut down of the mill, pending repairs.

Still a further object of the invention is to provide means for maintaining the accelerating lever at all times in operating position relatively to both the cam coöperating therewith and the tappet on the stamp carrying rod, and for insuring the engagement of said accelerating cam and lever in the manner designed.

To effect the foregoing objects, a stamp mill of my invention consists of the various features, combinations of features and details of construction hereinafter described and claimed.

In the accompanying drawings, in which my invention is fully illustrated,—Figure 1 is a sectional elevation of a stamp mill embodying my invention, taken substantially on the line 1—1 of Fig. 3. Fig. 2 is a side elevation of the upper portion of my improved stamp mill. Fig. 3 is a top plan section thereof on the line 3—3 of Fig. 2. Fig. 4 is a side elevation of the accelerating cam on an enlarged scale.

Referring now to the drawings, A designates the base of a stamp mill anchored to a suitable foundation B by means of stay bolts C the lower die supported in fixed position upon the base A, and D the upper movable stamp or die carried on the lower end of a rod E supported so as to be freely movable endwise in both directions in suitable bearings e on the machine frame.

F is a cam shaft journaled in suitable bearings f on the machine frame to which, in operation, rotation at a constant speed is im-

2 by means of a belt applied to a driving pulley F^1 secured to said cam shaft and connecting the same with a source of power, not shown.

5 G is a wiper cam secured to rotate with the shaft F, and H a collar or tappet on the rod E, the under surface of which projects into the path of travel of the cam G, whereby said tappet, together with the rod E and movable stamp or die D will be intermittently raised by the cam G and then released, allowing the same to fall.

10 The frame of the machine comprises lateral upright members I rigidly secured to the foundation B at their lower ends by means of tie rods i connecting said members I with angle plates i^1 anchored to the foundation B by means of stay bolts i^2 , and transverse frame members I^1 .

15 20 The stamps C and D are inclosed in a suitable casing J provided with an opening j through which the rock, ore, or other material to be crushed is delivered upon the lower, fixed stamp or die C, and with lateral openings j^1 provided with suitable screens through which the crushed material is carried as fast as it becomes sufficiently reduced, by means of the usual stream of water discharged into the casing J. This water escapes through 25 the screened openings j^1 into a trough j^2 which surrounds the casing J below the opening j^1 and is provided at its lower side with a discharge spout j^3 .

30 35 As regards the foregoing features the stamp mill may be of any desired or approved construction and will be readily understood by those skilled in the art from an inspection of the drawings.

40 Obviously the crushing effect of the stamp or die D will depend upon its weight, including the weight of associated parts, and upon its velocity when it strikes. As said movable stamp or die, however, travels only a comparatively short distance in operation 45 and starts with a velocity of zero, it is desirable to provide means for overcoming the inertia of the parts and imparting thereto a velocity which will render its crushing impact effective when it strikes the material resting on the lower die C. As herein previously stated, it has heretofore been attempted to effect this end by means of a pivoted lever one arm of which coöperates with the raising cam G while its free arm is adapted 50 to impinge upon a rigid shoulder of the rod which carries the movable stamp or die. As explained and for the reasons stated, however, this method has been found to be objectionable, and in my improved stamp 55 mill the means for accelerating the velocity of the movable stamp or die, are as follows: Pivoted upon the machine frame in suitable position is a bell crank lever 1, said lever being preferably secured to rock with a pivot shaft 60 65 2 journaled in suitable bearings 3 on the ma-

chine frame. Said bell crank lever comprises arms 4 and 5, of which the arm 4 extends over and is adapted to impinge upon a rigid shoulder on the rod E, as on the top of the tappet H. The arm 5 of this bell crank projects into the path of travel of a supplemental cam 6 secured to rotate with the shaft F, said cam 6 being so positioned, relatively to the cam G, that it will contact with the arm 5 of the bell crank lever 1 just as or momentarily after the cam G, having raised the tappet H and parts controlled thereby to the limit of their up stroke, passes out of engagement therewith, leaving the same free to descend.

70 75 80 The cam 6 is of the shape shown in Fig. 4 of the drawings, and its operative length is shorter than the operative length of the lifting cam so that it will pass out of engagement with the arm 5 of the bell crank lever 1 when the movable stamp or die D has reached a predetermined point in its down stroke, say when said stamp or die has passed through one-third of its stroke, in which position, excepting under extraordinary circumstances, it will still be a considerable distance above 90 the material resting on the lower die C. Obviously, by varying the shape of the operative surface of the cam 6, the kick of said cam and thus the extent to which the velocity of the movable die D will be accelerated, may be 95 varied as desired in any given case.

95 100 105 In order to maintain the arms 4 and 5 of the bell crank lever 1 in proper operative relation to the tappet H on the rod E and the cam 6, respectively, the arm 4 of said lever is pivotally connected to the tappet H by means of a link 7. As shown, said link 7 is connected to the lever arm 4 by means of a suitable stud bolt and to the tappet H by means of a stud or trunnion 8 on said tappet which engages a suitable bearing in said link 7. As shown, the stud or trunnion 8 is formed on a ring 9 fitted to a groove 10 formed adjacent to the upper end of the tappet H. To provide for assembling said ring 9 upon said head, it is made in sections secured together by suitable clamping bolts. The surface of the lever arm 4 which bears upon the tappet H is concentric with the point of pivotal attachment of said link to 110 said lever arm, thus providing for contact of said lever arm with said head in its different pivotal positions. In order to relieve the link 7 from all stress due to the action of the bell crank lever 1, provision is made for slight 115 play in the connection between the head H and lever arm 4. As shown, this is effected by making the ring or collar 9 slightly narrower than the width of the groove 10. It is obvious that said link 7 will at all times 120 maintain the bell crank lever 1 in proper operative relation to the tappet H and also to the cam 6 to secure the designed operation of the various parts.

125 130 To effect the object of my invention as it

relates to providing a safety device, whereby a member of the accelerating mechanism will be broken in a predetermined place and manner, in the event that it is subjected to an excessive strain, as, should the discharge openings from the casing J become clogged, resulting in the accumulation of an excessive amount of material therein, whereby the movable stamp or die D would be arrested before the cam 6 passed out of engagement with the lever arm 5, which would result either in stopping the mill or in breaking a part, the bell crank lever 1 is made in two sections, one section comprising the arm 4 and the other the arm 5, said sections being secured together by means of pins 11, one or both of said sections being mounted to turn freely on the pivot shaft 2 when they are disconnected from each other. The pins 11 are made strong enough to withstand the stresses to which said lever is subjected in its designed operation but are sufficiently weaker than other parts of said lever and than the cam 6 so that they will shear off before either said lever or cam is subjected to a stress which would break it. One section at least of said bell crank lever being free to turn on the pivot shaft 2 when the sections of said lever are disconnected, it is obvious that if the pins 11 are broken, the lever arm 4 will be unaffected by the movement of the lever arm 5 under the influence of the accelerating cam 6 and that the raising cam G and parts controlled thereby will be free to execute their regular cycle without interference. To repair the mill, in case said pins are sheared off, from any cause, it will only be necessary to drive out the broken parts of the pins and replace them with other pins, which can be done at a very slight expense, both as regards cost of material and time consumed in making the repairs.

I claim:—

1. In a stamp mill of the type set forth, the combination of a stamp rod having a single tappet thereon, a driven shaft journaled below said tappet and carrying a lifting cam and an accelerating cam, the operative length of said accelerating cam being shorter than that of the raising cam, a bell-crank

lever pivoted at a point above the cams and having one arm depending into the path of the accelerating cam and its other arm into the path of movement of the tappet, for the purpose set forth.

55

2. In a stamp mill of the type set forth, the combination of a stamp rod having a single tappet or collar, a driven shaft journaled below said tappet and carrying a lifting cam and an accelerating cam, a bell-crank lever pivoted at a point above the cams and having one arm depending into alinement with the accelerating cam and its other arm extending over upon the upper end of the tappet, and a pivotal connection between this latter arm and the tappet, for the purpose set forth.

60

3. In a stamp mill of the type described, the combination with a stamp rod and means intermittently raising and releasing said rod, of a driven shaft carrying an accelerating cam, and a bell-crank lever coöperating with said cam and a rigid portion of the stamp rod, the arms of said bell-crank lever being formed of separate sections one of which sections is rotatable freely on its pivot when disconnected from the other section, and shearing pins connecting the two sections of said bell-crank lever.

75

4. A stamp mill comprising a stamp rod provided with a tappet, a driven shaft carrying a raising cam and a separate accelerating cam, a bell-crank lever pivoted at a point above the cams and having one of its arms in line with the accelerating cam and its other arm extending over upon the upper side of the tappet, a link pivotally connecting this latter arm with the tappet, the impinging face of the arm being curved concentrically with the pivotal connection to the link, for the purpose set forth.

80

In testimony, that I claim the foregoing as my invention, I affix my signature in presence of two subscribing witnesses, this 28th day of May, A. D. 1907.
